UNITED STATES PATENT OFFICE.

GEORGE L. PHELPS, OF CHICAGO, ILLINOIS, ASSIGNOR TO INTERNATIONAL HARVESTER COMPANY, A CORPORATION OF NEW JERSEY.

GRAIN-BINDER.

No. 843,626.

Specification of Letters Patent.

Patented Feb. 12, 1907.

Application filed November 22, 1906. Serial No. 344,559.

To all whom it may concern:

Be it known that I, GEORGE L. PHELPS, a citizen of the United States, residing at Chicago, in the county of Cook and State of Illinois, have invented a new and useful Improvement in Grain-Binders, of which the following is a complete specification.

This invention relates to grain-binders of the type illustrated and described in United States Patent No. 398,466, which issued to B. F. Stewart February 26, 1889, and in which the knotter-shaft and needle-shaft are actuated through a crank and lever connection with an intermittently-rotating shaft, this latter shaft being in operative connection with the constantly-rotating packer-shaft. Constructions of this type as heretofore made were not well adapted to apply great power where needed and higher speed where possible. The present improvement is directed to the overcoming of such objections and to produce a construction which will be simple and highly efficient.

Referring to the accompanying drawings, Figure 1 represents a front end elevation of a grain-binder attachment embodying my invention. Fig. 2 is a side elevation of the forward end of the attachment shown in Fig. 1. Fig. 3 is a transverse horizontal section taken on the line 3-3 of Fig. 2. Figs. 4 and 5 are diagrammatic views illustrating the differential motion of the knotter-shaft with respect to its driving-shaft, Fig. 4 illustrating such motion as imparted by my improved construction, and Fig. 5 the same as imparted by the arrangement as heretofore employed and shown in the patent above mentioned.

In the type of binder herein illustrated, as will be seen in the patent to which reference has been made, the constantly-rotating packer-shaft has a clutch connection with the intermittently-rotating driving-shaft or other equivalent means which impart movement to the knotter-shaft, and this clutch mechanism is controlled by any suitable connection with the tripping device. As these last-mentioned parts constitute no feature of the present improvement and are very well understood in the art, their inclusion in the specification was not deemed necessary.

Referring to the accompanying drawings, 1 designates the binder-frame, only the forward end thereof being shown, and in the

upper branch 1' thereof is journaled the 55 knotter-shaft 2, while in the lower branch 1" is journaled the needle-shaft 3. To the knotter-shaft 2 is secured the ejector or discharge arms 4 and also the usual cam-gear 5, and to the needle-shaft 3 is fixed the 60 needle 6, the construction, function, and operation of which parts are so well known as to render further description unnecessary. To the binder-frame is also secured the usual 65 breast-plate 7 and stripper-arm 8.

In the lower portion of the frame 1 is journaled the driving-shaft 9 which is an extension of the packer-shaft, the packer-shaft not being shown. The said shaft extension or driving-shaft 9 has an intermittent rotation imparted thereto through a suitable trip-controlled clutch mechanism, as clearly shown in the patent mentioned, but a disclosure of which is not essential to a clear understanding of the present invention. It 75 need only be stated in this connection that the shaft 9 or equivalent thereof has imparted to it an intermittent rotation from the packer-shaft or other moving part of the machine, the movement occurring whenever 80 a bundle of grain is bound and ejected. This shaft 9 imparts movement to the other elements of the binder which are directly involved in my improvement, and hence may properly be termed an "intervallently-rotating" driving-shaft.

On the end of the driving-shaft 9 is formed the crank 10, with the wrist-pin 10', while the forward end of the needle-shaft 3 terminates on the crank 11. An adjustable pitman or link 12 connects the cranks 10 and 11 of the driving and needle shafts, respectively, and the crank 11 is given a longer arm than that of the crank 10, so that a complete rotation of the driving-shaft 9 will cause a rocking 95 movement of the needle-shaft 3.

In order to properly adjust the power which is applied to the knotter-shaft 2 to the resistance met by the discharge-arm's 4 thereon, it becomes necessary to provide a differential motion between the driving-shaft and knotter-shaft. A crank 13, having the wrist-pin 13', is fixed to the forward end of knotter-shaft 2, and on the wrist-pin 10' of the crank 10 is mounted the lever 14, the upper end of 100 which connects with the wrist-pin 13' of the crank 13 through the differential link 15. It is obviously necessary, in order to render op-

erative the construction just described to also provide a fulcrum for the lever 14. In the arrangement heretofore employed in such type of binder attachment a fixed fulcrum 5 was used and in consequence the proper differential motion could not be secured or could not be applied at the desired point in the path of travel of the discharge-arms. In the present improvement a movable fulcrum 10 is employed, thereby accelerating or retarding to the required degree and at the proper time the movement of the said arms. A laterally-projecting support is formed on the binder-frame 1 by the outwardly-extending bracket 16, formed, preferably, integral with the binder-frame and to which is fixed the arm 17. (See Fig. 3.) On the outer end of this arm 17 is pivotally mounted the link 18, while the inner end of said link pivotally connects with the lever 14, and thus forms a movable fulcrum for said lever. The connection between the link and lever is at a point substantially midway of the length of the lever. The path described by the fulcrum of the lever corresponds to the arc of a circle whose center is coincident with the pivotal center of the link 18 on the arm 17 and whose radius is equal to the length of said link.

30 In order to more clearly show the comparative retardation and acceleration of the knotter-shaft 2 with the discharge-arms 4 thereon resulting from my improved construction and that resulting from a fixed fulcrum, as in the construction of the patent of Stewart mentioned, diagrams illustrating such movement are shown in Figs. 4 and 5, Fig. 4 showing the lag or retardation in the former construction and Fig. 5 that in the latter. In these diagrammatic views 9' represents the driving-shaft; 2', the knotter-shaft; 10', the wrist-pin 10^a, and 13' the wrist-pin 13^a. The lever 14 is designated by the line 14', the differential link 15 by the line 15', and the link 18 by the line 18'. The arrows indicate the direction of movement of the wrist-pins in their path. a b c, &c., indicate the successive positions of the wrist-pin 10^a at successive and equal intervals of space 40 traversed, and a' b' c', &c., indicate the corresponding positions of the wrist-pin 13^a. To more clearly set forth the retardation and acceleration of the wrist-pin 13^a, the circle representing its path of travel is divided in 45 equal parts, which are marked a'' b'' c'', &c., and correspond in number with the successive positions a b c, &c., of the wrist-pin 10^a. It will be apparent from an inspection of the diagrams that when the motion of the wrist-pin 13^a is retarded the arc a' b', b' c', c' d', &c., will be less than a'' b'', b'' c'', &c., and the amount of such lag or retardation will be indicated by the arcs b' b'', c' c'', d' d'', &c. It will be observed from an inspection of Fig. 4 55 that the extent of these arcs indicating the

lag gradually increases up to the point f'', the arc f' f'' being the greatest. This point f'' corresponds to the position of the discharge-arms when ejecting the bundles, and hence to that position of the stroke where they encounter the greatest resistance. It will be understood also that when the lag is greatest the leverage is greatest, and hence the greatest power can be applied to the knotter-shaft and discharge-arms carried thereby. From 70 the point f'' the lag begins to grow less, indicating that the movement of the wrist-pin from this point is accelerated for the remainder of the revolution, the lag growing less until the initial-point a', where it becomes 80 zero. An inspection of Fig. 5, disclosing a diagram showing the movement resulting from the construction found in the Stewart patent, reveals no lag at the point f'', while the greatest lag d d is relatively small, so 85 small, in fact, as to be quite ineffective.

What I claim as my invention, and desire to secure by Letters Patent, is—

1. In a binder attachment for harvesters, in combination, a binder-frame, a knotter-shaft and a needle-shaft journaled in said frame, an intermittently-rotating driving-shaft, a crank connection between said driving-shaft and needle-shaft, a lever having a crank connection with the driving-shaft, and 90 a link connection with the knotter-shaft, the said lever imparting a differential motion to the knotter-shaft through said link connection a movable fulcrum for said lever, and means for guiding said fulcrum in a curved path, substantially as and for the purpose specified.

2. In a binder attachment for harvesters, in combination, a binder-frame, a knotter-shaft and a needle-shaft journaled in said frame, an intermittently-rotating driving-shaft, a crank connection between said driving-shaft and needle-shaft, a lever having a crank connection with the driving-shaft, and a link connection with the knotter-shaft, the said lever imparting a differential motion to the knotter-shaft through said link connection and a fulcrum for said lever adapted to move in the arc of a circle, substantially as and for the purpose specified.

3. In a binder attachment for harvesters, in combination, a binder-frame, a knotter-shaft and a needle-shaft journaled in said frame, an intermittently-rotating driving-shaft, a crank connection between said driving-shaft and needle-shaft, a lever having a crank connection with the driving-shaft, and a link connection with the knotter-shaft, the said lever imparting a differential motion to the knotter-shaft through said link connection, a movable fulcrum for said lever, a laterally-projecting bracket fixed to said binder-frame, and a fulcrum-link pivotally mounted on said bracket and pivotally connecting with said lever, substantially as and for the purpose specified.

4. In a binder attachment for harvesters, in combination, a binder-frame, a knotter-shaft and a needle-shaft journaled in said frame, intermittently-rotating driving means, a lever interposed between said driving means and knotter-shaft, a movable fulcrum for said lever, and means for guiding the said fulcrum to cause retardation of the movement of the knotter-shaft at that portion of its stroke where it encounters the greatest resistance and to cause an acceleration of the movement of said shaft at that portion of its revolution where it does little work.
5. a lever interposed between said driving means and knotter-shaft, a movable fulcrum for said lever, and means for guiding the said fulcrum to cause retardation of the movement of the knotter-shaft at that portion of
